RENÉ DE M. TAVEAU, OF ELIZABETH, NEW JERSEY, ASSIGNOR, BY MESNE ASSIGNMENTS, TO THE TEXAS COMPANY, OF NEW YORK, N. Y., A CORPORATION OF DELAWARE

EXTRACTION PROCESS

Application filed May 15, 1925. Serial No. 30,430.

My invention relates to a process for extracting materials with a solvent and has special reference to such a process and apparatus in which a volatile solvent is employed.

In the refining of hydrocarbon oils such as lubricating oils it is customary to treat the oils with varying amounts of sulphuric acid and after settling and drawing off the acid sludge the oil may be washed with aqueous caustic soda and finally with water alone. Considerable amounts of the valuable portions of oil are thus destroyed while the resultant acid sludge containing the main part of the impurities is practically worthless or at the most of little value. Furthermore the treatment of oil in such a manner involves complicated chemical processes and such treatment, therefore, requires careful technical supervision to insure a product acceptable to the user.

I have found, however, that this method may be improved upon by extracting the unrefined material with a solvent to produce pure oil and a residue containing the impurities. This residue may be employed as fuel oil or for other suitable purposes after the extraction of the desired oil to any extent considered practicable. The solvent utilized should be volatile so that it may be vaporized from the extracted oil and be recirculated in the process. By the use of a closed system the loss of solvent is exceedingly small and costs are low.

The success of such a process depends to a large extent upon the oil to be refined and the solvent selected. I have found while working with lubricating oils that isopropyl alcohol is a suitable solvent for the pure oil while asphaltic and other impurities remain undissolved therein. The alcohol has a specific gravity less than that of lubricating oil and consequently may be introduced into the bottom of the body of oil to percolate up through it, extracting a portion during its passage. Solvents having a specific gravity greater than the material being extracted may also be used but in such case provision must be made for introducing the solvent at the

top and withdrawing it from the bottom of the vessel.

An additional advantage to be derived from my invention resides in its application to the refining of heavy asphaltic base residuum and the like, as for example, the material commonly known as "flux oil". It has been found that such residuum may easily be treated in accordance with my process for the recovery of valuable lubricating oils therefrom, while by the methods usually practiced such recovery would be entirely impractical because of the excessive amounts of chemicals required to properly purify the oil and the comparatively small amount of refined material ultimately received.

For a better understanding of my invention reference may be had to the accompanying drawings in which Figure 1 is a diagrammatic showing of a plant apparatus for carrying out my process, while Figure 2 is a partially sectional view of laboratory apparatus. Figure 3 is an enlarged view of the top portion of the extraction vessel of Figure 2. Figure 4 is a sectional view of an inner extraction vessel for the apparatus shown in Figure 2 and to be employed when extracting with a solvent heavier than the oil.

In Fig. 1, 1 is the extraction vessel which may be of the usual agitator type employed for acid treatment of oils and is provided with coils 2 by means of which the temperature of the material to be extracted may be maintained within the desired range by the circulation of steam or water. The extractor 1 is also provided with an inlet pipe 3 for admitting oil or other material to be extracted and with an outlet pipe 4 for the withdrawal of the extracted residue. Pipe 5 leads the solvent into the bottom of the extractor 1 from the solvent stills 6 and 7. An overflow pipe 8 allows solvent containing extracted material to pass into the settling chamber 9 which is also maintained at the same temperature as the extractor 1 by means of the heating or cooling coils 10. A pipe 11 siphons solvent from the chamber 9 when the solvent reaches the proper level therein and permits the solvent to flow to still 7 through the valve 12 or to still 6 through the valve 13. The stills 6

and 7 are provided with drawoff pipes 14 and 15, respectively, having suitable control valves therein and lead to the pipe 16, whereby the residual extract in either of the stills may be drawn off to a suitable container. The risers 17 and 18 lead from the stills 6 and 7 to pipe 5 and have valves 19 and 20 for controlling the flow of solvent vapors. A steam line 21 leads to a distributor 22 near the bottom of the extractor 1 for the introduction of live steam into the extracted residue to volatilize therefrom any solvent which it may retain at the end of the extraction, the uncondensed steam and solvent vapors passing out through the valve 23 and into the condenser 24 to be recovered.

To operate the process with this apparatus the extractor 1 is filled with crude petroleum residuum or other material to be extracted, to a point below the overflow pipe 8. Solvent from one of the stills, as for instance 6, is vaporized and is led through pipe 5 to the bottom of the extractor 1. The solvent, having been condensed in its passage through pipe 5, enters the oil, gradually flows up through the same and passes out through pipe 8 when sufficient solvent has collected to rise to that level in the extractor 1. The chamber 9 then becomes filled with solvent containing extracted pure oil and overflows through pipe 11 and since distillation is being carried on in still 6 the solvent is allowed to collect in still 7 by opening the valve 12 and maintaining the valve 13 in closed position. When practically all of the solvent in still 6 has been vaporized heating thereof is discontinued and distillation is begun in still 7. To accomplish this, valve 20 is opened while valve 19 is closed, allowing the vapors from still 7 to enter the extractor through pipe 5, while the valve 12 is closed and the valve 13 opened to permit accumulation of the extracted material and solvent in the still 6. This operation is continued until substantially all of the volatile solvent is vaporized from the extracted oil in still 7, at which point the oil may be drawn from still 7 by opening the valve in the pipe 15. Distillation then is carried on from still 6 as before. As the removal of extracted oil reduces the volume of the unrefined oil in extractor 1, additional unrefined oil may be introduced through pipe 3 or the introduction of that material may continuously take place during the extraction by the proper adjustment of the valve in pipe 3.

After substantially all of the extractable oil has been obtained from the material in extractor 1, circulation of the solvent may be discontinued temporarily while steam is introduced into the body of residue through the pipe 21 and distributor 22. The valve 23 should be opened to permit the escape of uncondensed steam and the solvent vaporized thereby to be condensed in the condenser 24.

The residue in extractor 1 may then be drawn

off by opening the valve in pipe 4 to flow to suitable storage for use as fuel oil or for other purposes and another charge of unrefined oil introduced into the extractor 1.

In Fig. 2, the extractor consists of an outer jacket 30, an inner extraction vessel 31 in which the material to be extracted is maintained and a cylindrical partition 32 serving the double purpose of providing a collection chamber 33 for the solvent overflowing from vessel 31 as well as a chamber 34 for the circulation of cooling or heating fluid around the extraction vessel 31. The latter is provided with a gallery or settling chamber 35 at the top thereof to permit particles of material being extracted to settle out and be returned to the main body of material. A pipe 36 leads the solvent containing extracted material from the chamber 33 to the still 37 which may be heated in any suitable manner as by a steam bath or a Bunsen burner. Pipe 38 leads the solvent vapors generated in the still 37 to the condenser 39, an extension 40 of which introduces the condensed solvent into the bottom of the extraction vessel 31. Pipe 38 is preferably jacketed along its vertical portion to prevent undue condensation of the solvent. In case it is desired to operate the extraction process at or near the boiling point of the solvent employed the apparatus may be provided with a condenser 41 connected to chamber 33 and extraction vessel 31 to condense and return to chamber 33 any solvent which may be vaporized therefrom.

The laboratory apparatus just described operates in substantially the same manner as the plant apparatus shown in Figure 1, the extracted material collecting in still 37 together with solvent overflowing from the extraction vessel 31. It will be observed that provision has been made for carrying out the extraction operation at any desired temperature up to the boiling point of the solvent but entirely independent of that factor. This permits taking advantage of the relative solubilities of the components of the refined oil in the solvent employed, by arranging the temperature of extraction to conform to the temperature of greatest relative solubility of pure oil and greatest relative insolubility of impurities in the solvent. By utilizing this principle the extraction may be accomplished under the most favorable temperatures which are to be determined in each case by the particular solvent employed and the particular material being extracted.

When extracting the oil with a solvent having a specific gravity greater than that of the oil under the conditions of extraction, it is desirable to substitute the extraction vessel 42, shown in Figure 4, for the extraction vessel 31 indicated in Figure 2. The extension 40 of the condenser 39 may be disconnected when using the extraction vessel 42 so that the condensed solvent will drop from the end

of the condenser 39 into the top of the extraction vessel 42 and the solvent, being heavier than the oil to be extracted, percolates down through the oil extracting a portion 5 during its passage and collects at the bottom of the extraction vessel whence it will rise in the overflow tube 43 and pass into the collection chamber 33. The solvent containing extracted material will then flow from chamber 10 33 to still 37 through pipe 36 as previously described.

The apparatus shown and described is especially adapted for extracting hydrocarbon oils. It may, of course, be used for extracting 15 other liquids or solid substances where it is desired to control the temperatures of extraction. While I have thus specifically described my invention the specific examples chosen to illustrate the same are not to be 20 construed as limiting the invention, the principles of which are set forth in the appended claim.

What I claim is:

A process for the recovery of valuable lubricating oil from an asphalt base residuum 25 which comprises treating the residuum with isopropyl alcohol, separating the oil-alcohol solution from the undissolved asphaltic matter, and evaporating the isopropyl alcohol 30 to recover the lubricating oil.

In witness whereof I have hereunto set my hand this 12th day of May, 1925.

RENÉ DE M. TAVEAU.
